UNITED STATES PATENT OFFICE.

NATHAN KASDAN, OF NEW YORK, AND RICHARD F. LANDWEHR, OF WOODSIDE, NEW YORK, ASSIGNORS TO MAJESTIC METAL SPECIALTIES, INC., OF NEW YORK, N. Y., A CORPORATION OF NEW YORK.

COSMETIC-PENCIL CONTAINER.

Application filed August 6, 1928. Serial No. 297,706.

Our invention relates to cosmetic pencil containers and refers particularly to devices of this character in which the opening and closing of the container extends or withdraws a cosmetic pencil carried thereby.

Cosmetic pencils are usually carried in containers to protect them from contamination and from which they can be extended for use.

10 As these containers are usually of an elongated formation in order to accommodate the pencil, it is evident that a cover must be supplied for the open end of the container when the pencil is in withdrawn position.

15 Our invention overcomes the necessity of a separate cover and separate moving means for the pencil and presents a device for the purposes described in which the opening of the container causes the pencil to be extended therefrom and the closure of the container withdraws the pencil into the container.

20 The above, and other, valuable features of our device will be evident upon a consideration of our specification and its accompanying drawings.

25 In the accompanying drawings illustrating one form of the device of our invention, similar parts are designated by similar numerals.

30 Figure 1 is a side view of one form of our device in closed position.

Figure 2 is an end view of Figure 1.

Figure 3 is a side view of the device of Figure 1 in open position.

35 Figure 4 is a section through the line 4—4 of Figure 2.

Figure 5 is a section through the line 5—5 of Figure 1.

40 Figure 6 is a section through the line 6—6 of Figure 1.

Figure 7 is a side view of the operating arm of the device of Figure 1.

Figure 8 is an end view of the device of Figure 7.

45 Figure 9 is a side view of the pencil holder moving mechanism.

Figure 10 is a section through the line 10—10 of Figure 9.

50 Figure 11 is a perspective view of the pivotal assembling pin.

The particular form of the device of our invention illustrated in the accompanying drawings comprises a casing formed of the two members, one having the side 12 and the

angular ends 13 and 14, and the other having 55 the side 15 and the angular ends 16 and 17, the ends 13 and 16 abutting upon each other and the ends 14 and 17 abutting upon each other, the assembled elements forming a casing with opposite parallel sides 12 and 15 60 and opposite exposed angular ends 13 and 14, closed at one end and open at the other.

The casing side 12 has the longitudinal flange 18 and the casing side 15 has the longitudinal flange 19. 65

The lower portion of the casing has the aligned annular openings 20, 20.

Within the casing is a revoluble cylindrical spring carrier 21 closed at one end 22, the end 22 having a centrally positioned 70 rectangular opening 23 therein.

A resilient member 24 is fixedly attached to the spring carrier 21, extends upwardly within the casing and carries a cosmetic pencil holder 25 at its upper, or free, end. 75

A U-shaped operating arm exterior of the casing comprises the two sides 26, 26, each carrying a longitudinal flange 27, a circular flange 28 and having a cut-out portion 29, the two sides 26, 26, being connected by the 80 member 30 which acts as a cover for the open end of the casing when the device is in closed position. Each side 26 also carries a lower circular flange 31.

The operating arm sides 26, 26 have 85 aligned rectangular openings 32, 32.

The several movable parts are assembled by a pivotal operating pin comprising an annular central portion 33, extended into the two-sided flat, or rectangular portions 90 34, 34 which are extended into the annular portions 35, 35.

When the device is assembled, as shown particularly in Figure 5, the two rectangular elements 34, 34 of the pin 33 pass through the annular openings 20, 20 of the casing and are revoluble therein, and through the rectangular openings 32, 32 of the operating arm, the annular portions 35, 35, passing through annular openings in the base 36, 100 and flanged over to connect the several elements.

The operation of the device is as follows:—

With the device in closed position, as 105 shown in Figure 1, the thumb and finger of one hand are placed within the circular flanges 28, 28 of the operating arm, the

thumb and finger of the other hand are placed upon the casing within the cut-outs 29, 29 and the hands separated, thus bringing the device into the position shown in 5 Figure 3.

As the rectangular portions 34, 34 of the pivotal pin are positioned within rectangular openings in the spring carrier and the operating arm, and as the pivotal pin is revolute within annular openings within 10 the casing, it is evident that if the casing be retained in fixed position and the operating arm moved the spring carrier will be revolved.

15 As the operating arm is moved from closed position, the member 30 will be removed from over the open end of the casing, a further movement of the arm causing the revolution of the spring carrier to move the resilient member 24 and the pencil holder 25 to move upwardly thus exposing the cosmetic pencil 37 carried by the holder 25.

20 The movement of the operating arm toward closed position causes the resilient member 24 to be wound around the spring carrier, thus withdrawing the cosmetic pencil 37 into the casing.

25 It will thus be seen that our device presents a cosmetic pencil container, in which the pencil is protected when closed and the opening of which automatically causes the pencil to be extended beyond the casing to any desired extent.

30 We do not limit ourselves to the particular size, shape, number, arrangement or material of parts as shown and described as these are given simply as a means for clearly describing our invention.

35 What we claim is:

1. In a cosmetic pencil container, in combination, a casing open at one end, a revolute spring carrier within the casing, a resilient member attached to the spring carrier and longitudinally movable within the casing, a pencil-holder carried by the free end of the spring carrier, an operating arm exterior of the casing and pivotal means connecting the spring carrier and the operating arm whereby a movement of the latter will move the pencil holder longitudinally within the casing.

2. In a cosmetic pencil container, in combination, a casing open at one end, a revolute spring carrier within the casing, a resilient member attached to the spring carrier and longitudinally movable within the casing, a pencil-holder carried by the free end of the spring carrier, an operating arm exterior of the casing and a pivotal member revolute within the casing and non-revolute within the spring carrier and the operating arm.

3. In a cosmetic pencil container, in combination, a casing open at one end, a revo-

luble spring carrier within the casing, a resilient member attached to the spring carrier and longitudinally movable within the casing, a pencil-holder carried by the free end of the spring carrier, an operating arm exterior of the casing and pivotal means connecting the spring carrier and the operating arm whereby movements of the latter will wind and un-wind the resilient member upon the spring carrier.

70

75

4. In a cosmetic pencil container, in combination, a casing open at one end, a revolute spring carrier within the casing, a resilient member attached to the spring carrier and longitudinally movable within the casing, a pencil-holder carried by the free end of the spring carrier, an operating arm exterior of the casing and a pivotal member revolute within the casing and non-revolute within the spring carrier and the operating arm whereby a movement of the operating arm will move the pencil holder longitudinally within the casing.

80

85

5. In a cosmetic pencil container, in combination, a casing open at one end, a revolute spring carrier within the casing, a resilient member attached to the spring carrier and longitudinally movable within the casing, a pencil-holder carried by the free end of the spring carrier, an operating arm exterior of the casing, a casing cover carried by the operating arm and pivotal means connecting the spring carrier and the operating arm whereby a movement of the latter will move the pencil holder longitudinally within the casing and open and close the open end of the casing.

90

95

6. In a cosmetic pencil container, in combination, a casing open at one end, a revolute spring carrier within the casing, a resilient member attached to the spring carrier and longitudinally movable within the casing, a pencil-holder carried by the free end of the spring carrier, an operating arm exterior of the casing, a casing cover carried by the operating arm, and a pivotal member revolute within the casing and non-revolute within the spring carrier and the operating arm whereby movements of the operating arm will move the pencil holder longitudinally within the casing and cover and un-cover the open end of the casing.

100

110

115

7. In a cosmetic pencil container, in combination, a casing open at one end, a revolute spring carrier within the casing, a resilient member attached to the spring carrier and longitudinally movable within the casing, a pencil-holder carried by the free end of the spring carrier, an operating arm exterior of the casing, a casing cover carried by the operating arm and a pivotal member revolute within the casing and non-revolute within the spring carrier and the operating arm, the movement of the arm un-

125

130

covering the casing, moving the pencil holder longitudinally toward the open end of the casing.

8. In a cosmetic pencil container, in combination, a casing open at one end, a revolvable spring carrier within the casing, a resilient member attached to the spring carrier and longitudinally movable within the casing, a pencil holder carried by the free end 5 of the spring carrier, an operating arm exterior of the casing, a casing cover carried by the operating arm and a pivotal member revolvable within the casing and non-revolu-

ble within the spring carrier and the operating arm, the movement of the arm uncovering the casing, moving the pencil holder longitudinally toward the open end of the casing and the movement of the arm toward covering position moving the pencil holder longitudinally away from the open 15 20 end of the casing.

Signed at New York city in the county of New York and State of New York this 4th day of August, 1928.

NATHAN KASDAN.

RICHARD F. LANDWEHR.
